CODING, DECODING, AND CODE SENSING MECHANISMS FOR SORTING APPARATUS

Robert Gourdon, Paris, France, assignor to Societe Anonyme dite: Centre d'Etudes M. B. A. (Mecanique Ballestique, Armeement), Paris, France

Application July 22, 1952, Serial No. 300,160

Claims priority, application France January 16, 1946

20 Claims. (Cl. 214—11)

This invention relates to sorting or classifying apparatus and particularly to apparatus for sorting individual articles into a large number of classifications. It is described herein as applied to apparatus for sorting mail in accordance with its destination. Certain features of the invention are of particular utility in connection with mail sorting apparatus, while other features are of more general utility.

This application is a continuation-in-part of my co-pending applications for United States patents, Serial No. 722,197, filed January 15, 1947, for Apparatus for Indexing Articles, now abandoned; Serial No. 765,946, filed August 4, 1947, for Apparatus for Sorting Articles Such as Mail, now Patent No. 2,669,365; Serial No. 17,984, filed March 30, 1948, for Methods and Means for the Sorting and Classification of Documents or Articles, now Patent No. 2,696,919; and Serial No. 252,383, filed October 20, 1951, for Portable Indicating Holders and Settable Indicators Therefor. The last mentioned application is itself a continuation-in-part of Serial No. 765,946, Serial No. 17,984, above mentioned, and Serial No. 722,198, filed January 15, 1947, for Holders with Adjustable Identifying Codes and Arrangements Relating Thereto (now abandoned).

The subject matter of this application may be used with the conveying apparatus for use in a sorting or classification system disclosed in my application Serial No. 17,984 filed March 30, 1948, now Patent No. 2,696,919.

A complete system for sorting or classification of articles and utilizing the present invention includes a number of portable holders for the articles, which may be letters. These holders carry settable indicating elements by which the classifications of the articles, such as the destinations in the case of letters, may be registered so as to be apparent to a sensing mechanism. The system includes a sorting or indexing station, at which the letters are inserted in individual holders, which holders simultaneously have their respective indicating elements set in accordance with the destination of the letter inserted therein. The holders are then transferred from the indexing station by means of suitable conveying apparatus to a sorting station. Where the number of classifications is large, as is the usual case in mail classifying apparatus, the holders may pass through one or more pre-sorting stations before reaching the final sorting station.

At each pre-sorting station, there are provided one or more sensing mechanism to check each holder to determine the setting of the indicating elements thereon. Each sensing mechanism is set for a pre-determined destination or group of destinations according to an established code. When it encounters a holder whose indicating elements are set for that destination or group, it withdraws that holder from the conveyor which brought it to the pre-sorting station and transfers it to another conveyor which directs it either to a second pre-sorting station or to a final sorting station. At the final

2

sorting station, there are provided similar sensing mechanisms, each of which unloads the letters or other articles from those holders whose indicating elements are set in its code.

Application Serial No. 252,383, mentioned above, shows and claims the portable indicating holders and the settable indicators used in those holders. Application Serial No. 17,984, also mentioned above, shows and claims the conveyor apparatus used between the stations in the system and the means for loading and unloading holders into that conveyor apparatus. The present application is directed to the indexing or coding mechanism by which the indicators on the holders are set in accordance with the destinations of the letters and also to the code sensing mechanism which control the movement of the holders through a succession of branching paths to a particular receiving bin.

An object of the invention is to provide mechanism for simultaneously setting a plurality of indicator elements in different selected positions.

Another object is to provide improved setting mechanism of the type described, in which each indicator element is movable to a plurality of positions, and including means for selecting any of a large number of combinations of positions for said elements.

Another object is to provide improved apparatus for placing articles to be classified in individual holders, and simultaneously setting indicator elements on the holders to register the classifications of the individual articles placed therein.

Another object is to provide improved means for sensing the code settings of a number of indicator elements simultaneously and for performing control operations in accordance with such settings.

Another object is to provide improved code sensing apparatus of the type described, together with means responsive to that code setting to determine the path of travel of the holder from the sensing apparatus.

Another object is to provide improved code sensing apparatus of the type described together with means responsive to that code setting to empty the holder.

The foregoing and other objects of the invention are attained by providing at the indexing station a mechanism for setting the indicator elements on the holders, which operation is hereinafter referred to as "coding," a control panel for the coding mechanism, and means for making visible to an operator at the control panel the letters being placed in the holders. The control panel includes a number of selectively operable switches, one for each classification. As each letter becomes visible, the operator actuates a switch corresponding to its destination. Each switch when operated causes the energization of a plurality of electromagnets in a controller. The controller preselects a number of indicator setting tools to be moved on a subsequent control operation and also preselects the distances through which the respective setting tools are to move in that control operation. The selection is determined by the particular electromagnet or electromagnets controlled by the switch. After the preselection is complete, the operator moves a control lever which causes the letter to be inserted in a holder and also causes the selected indicator setting tools to engage and set the indicator elements on that holder. As each holder approaches the position where it receives a letter and has its indicating elements set, it passes a decoding device which resets all its indicating elements to a predetermined neutral position so that all the indicating elements are in that position when they are engaged by the setting tools of the coding mechanism.

After a letter is inserted in a holder and the indicating elements on the holder are set, the holder is transferred by suitable conveyor apparatus to a presorting or final

sorting station. When a holder carrying a letter reaches a pre-sorting or final sorting station, a code sensing mechanism is moved into engagement with its indicating elements. This sensing mechanism is set for a predetermined code or group of codes. When it encounters a holder whose code corresponds to this setting it seizes that holder and withdraws it from the conveyor mechanism on which it has been moving and transfers it to another conveyor leading eventually to an unloading station. At the unloading station another code sensing mechanism checks the code of the indicating elements and if it is correct operates suitable mechanism for emptying the letter from the holder into a bin corresponding to its destination. The empty holder is then returned to the indexing station by suitable conveyor apparatus.

Other objects and advantages of my invention will become apparent from the consideration of the appended specifications and claims, taken together with accompanying drawings in which

FIGS. 1 TO 3.—THE HOLDER

These figures illustrate a portable indicating holder 1, which is more completely described and claimed per se in my copending application, Serial No. 252,383, previously mentioned.

The holder 1 is constructed in the shape of a pocket, open at its upper end and comprising a front wall 2, a rear wall 3, and thickened side walls 4. Outer and inner reinforcing plates 5 and 6 are shown covering the side walls.

The pocket has a bottom flap 7 in the form of a plate riveted on the lower part of the wall 2 and sufficiently flexible so that it may be opened. When the flap is opened, the holder pocket is emptied by gravity.

The bottom flap 7 is self-biased to its closed position, in which position it engages the rear wall 3. It may be opened by means of a pair of opening rods 8 which extend downwardly through suitable guides within the pocket, and have their lower ends engaging the flap 7. The upper ends of the rods 8 are accessible through the open top of the pocket and are provided with flanges 8a. When the rods 8 are depressed to open the flap 7, the flap engages the outer surfaces of the rods and frictionally holds them against the rear wall 3. The flap 7 is thereby maintained open until the rods 8 are positively moved upwardly. This upward movement of rods 8 may readily be accomplished with the aid of flanges 8a, either manually or with a suitable mechanical device for engaging and lifting these flanges.

The rear wall 3 is longer vertically than the front wall, so as to provide upper and lower extending flanges. Both flanges are adapted to engage slots in a supporting structure so that the holder is held vertical. The upper flange is provided with a central notch 3a and the lower flange with notches 3b near its ends. These notches may be engaged by supporting or guiding rails so as to maintain a stack or group of holders in alignment.

Four pieces 9 in the shape of flat inwardly opening hooks are attached to the upper and lower ends of the side walls 2. These hooks facilitate endwise movement of the holder, either manually or by a mechanical device.

The side walls 4 are each provided with a number 40 of recesses 10 (Fig. 3). The reinforcing plates 5 are provided with openings 11 aligned with the recesses 10. An indicating element 12 is located in each of these recesses.

Each indicating element 12 comprises a cylindrical body 55 with a conical rear end 12a, and a diametrical rib 12b on its front end. The rib 12b has radially projecting tips 12c.

The recesses 10 are generally of the same form as the elements 12. Each recess 10 has a cylindrical portion 10a which receives the body of the element 12 and is slightly larger in diameter so that the body is freely rotatable therein. The outer end of this cylindrical portion 10a terminates at a tapered shoulder 10b leading to another cylindrical portion 10c of enlarged diameter. The tips 12c are rotatable and translatable in the portion 10c of the recess. Engagement of tips 12c with shoulder 10b limits the inward movement of the element 12, whereas engagement of tips 12c with the edge of plate 5 limits its outward movement.

The edge of plate 5 around each opening 11 is bent inwardly to form a frusto-conical portion 11a, and notches 11b are cut therein. These notches are provided in diametrically opposed pairs.

Each indicating element 12 is biased toward the outer end of its recess by a flexible leaf spring 13 which is

shown as being formed from the inner reinforcing plate 6 by a stamping and cutting operation. The conical end 12a of the indicating element projects into an opening 13a formed in the leaf spring 13. When the rib 12b is aligned with a pair of notches 11b, the leaf spring 13 holds the rib in the notches and angular movement of the element 12 is thereby prevented.

In order to change an element from one angular position to another, it is necessary to push it inwardly in opposition to the leaf spring 13 so as to release it from the two notches with which it has been engaged, and then to turn it while holding it inwardly. If the element 12 is turned to bring the rib 12b into alignment with another pair of notches and then released, the leaf spring 13 again forces the rib forward into the new pair of notches, thereby retaining the element in a new angular position. It is almost impossible for any accidental impact or vibration to produce a combination of forces that would be capable of translating and rotating an indicating element to change its indicating position once it has been set in the notches 11b. Furthermore, since the element 12 is always held securely completely within the recess 13, it cannot readily come into contact with any external object which might accidentally change its position. The inwardly bent portion 11a of the plate 5 blocks the outer end of the recess 10 sufficiently to prevent movement of the element out of the recess and to protect the element against accidental contacts with external objects.

The side walls 3 and plates 5 are provided with a central, inwardly tapered recess 5a which cooperates with other structures to be described so as to guide and center the holder 1.

The positions of the indicating elements are observable from outside the holder, either by visual inspection or by the use of sensing tools. It should be noted that the observation of these elements can be carried out either one element at a time or all elements simultaneously. When carried out simultaneously, a number of tools must be used, corresponding to the number of elements. Furthermore, these sensing or identifying operations can be performed when the holders are stacked, since the indicating elements are located in the side walls of the holders, which side walls are accessible when the holders are stacked.

Each indicating element has four distinguishably different indicating positions. Each element by itself is therefore capable of giving four indications, each having a meaning established by any arbitrarily selected code. For example, the position shown in Fig. 2, wherein the rib 12b is vertical, may be called the normal position. The element 12 may be rotated to three other indicating positions, respectively 45°, 90° and 135° from the normal position. If two elements are used together, there are sixteen possible combinations of element positions and therefore sixteen different possible code indications. Eleven elements, as shown in Fig. 1, can give a number of indications equal to four to the eleventh power, or 4,194,304.

When these holders are used, for example, in a mail sorting system, it is possible that a simple system might only require four classifications, and it would then be only necessary to use one indicating element on each holder. In a very complex sorting system, there may be thousands of classifications. In such a system, a combination of indicating element positions for each classification is established by an arbitrarily assigned code.

It would be possible to use one group of two or three elements to establish a state classification, another group to establish a city classification, etc.

Since indicating elements are provided on both ends of the holder, it is possible to have the holder indicating elements set or coded at both ends. In that event, a sensing device adjacent one end of the holder can check it for one code while another sensing device at the oppo-

site end of the holder checks it for a different code at the same time.

In a complex system, several successive sensing or identifying operations may be required. It is therefore essential that the position of the indicating element should not be disturbed by the sensing operation. The structure described above meets this requirement, since the positions of the indicating elements may be sensed by a linear movement of the sensing tool, while a change in position or setting of the element requires a linear movement of the setting tool followed by a rotary movement.

FIGS. 4-5.—CONVEYOR BLOCK

The conveyor block as illustrated in these figures is shown and claimed per se in my copending application Serial No. 765,946, previously mentioned. It is illustrated herein as part of a preferred form of mechanism for conveying the portable holders between the indexing station and the sorting stations.

Although this conveying mechanism is not claimed herein, a disclosure of it is necessary in order to disclose a complete sorting system, and in order to make clear many of the advantages of the invention claimed herein.

As shown in Fig. 4, the conveyor block comprises a box-shaped frame 14, of generally rectangular cross-section and having its sides open. The inner surface of the top and bottom of the frame 14 are corrugated or grooved as shown at 15, for the purpose of receiving the top and bottom edges of the rear walls 3 of the holders 1 when they are slid laterally into the conveyor block. When the top edge of a wall 3 is received in one of the upper grooves and the bottom edge in the opposite lower groove, the holder is maintained vertical, even though there are no other lateral supports.

The side edges of the frame 14 are reinforced by outwardly extending flanges 16 and 17, illustrated as being of channel-shaped cross-section. Hollow cross braces 18 are provided between the side flanges 16 and 17 at the four corners of the block and at the center of its top and bottom, as shown in Fig. 4. The side flanges and braces contribute to the stiffness of the block and also serve as locating surfaces for positioning the blocks accurately at the various working stations. They are also used as gripping surfaces when transferring the blocks from one conveyor to another.

When the receptacles are placed within a block, they may be locked there by a rod 19 which extends longitudinally of the block adjacent the middle of the top of the frame 14. In its unlocking position, rod 19 is above the top of the frame 14, so that it is outside the frame. The frame 14 has an elongated central aperture 14a just under the rod 19. The rod 19 may move downwardly through the aperture 14a and engage the notches 3a in the centers of the upper edges of the holders 1 within the block. When the holders 1 are so engaged by the rod 19, they are locked against transverse movement out of the block.

The rod 19 is supported on the ends of arms 21 attached to a shaft 20 journaled on spaced supports 20a, which are mounted on the frame 14. A torsion spring 22 encircles the shaft 20 and biases it to the position shown in Fig. 5 wherein the rod 19 has moved downwardly through the aperture 14a into a position to engage the holders 1 within the block. The ends of shaft 20 extend beyond the ends of frame 14, and both ends of the shaft 20 are provided with downwardly depending hooked arms 23 which may be utilized to rotate the shaft and lift the rod 19 to unlock the holders 1. For example, the arm 23 may be rotated by vertical movement of the block into a position where the arm 23 engages a stationary lug 24 (see Fig. 5).

Notches 25 are provided in the end portions of the side frame members 16 and 17, for guiding and supporting the blocks at certain times. These notches are located

below the lowest position of the arm 23, so that a member inserted into the two notches and spanning the block does not engage the arm 23.

FIGS. 6-16.—INDEXING STATION

Figs. 6-9, mechanism for handling letters, holders and blocks

The indexing station is an apparatus or machine in which incoming letters are placed individually in holders and the holders have their indicating elements set or coded in accordance with a pre-established code to indicate the destinations of the letters. The indexing station receives unsorted letters and blocks filled with empty holders whose indicating elements are set at random, and discharges blocks filled with holders each containing one letter and having its indicating elements set or coded to indicate the destination of that letter.

The path of movement of the letters into the machine will first be described. The letters are inserted in the machine in a stack such as shown at 26 in Fig. 7. The stack rests in a chute 27 which slants downwardly toward the operator's end of the machine which is at the right in Fig. 7. A suitable weight 28 is placed in the chute behind the stack 26 to force the letters forward. A belt 31 supported on suitable rollers 32 forms a portion of the bottom of the chute 27 and facilitates the forward movement of the stack 26. A glass plate 29 extends across the front of the chute, so that the leading letter in the stack is pressed against it, and the address on that letter is visible through the glass to the operator in front of the machine. A lamp 30 is suitably mounted above the plate 29 to illuminate the leading letter. Near its forward end the bottom of chute 27 is provided with one or more apertures 33, which are connected to any suitable source of air under light pressure. The air issuing from the apertures 33 separates the leading letter in the stack from those behind it and presses it lightly against the plate 29. The plate 29 is slanted slightly, with its lower end extending forward and spaced from the front end of the chute.

A mechanism is provided for removing the front letter from behind the plate 29 and conveying it downwardly along a guide wall 37 into a holder 1 positioned below it. The holder which receives the letter is the forward one of a stack of several such holders which are passing through the machine. As the letter travels from the glass plate 29 to the holder 1, it passes through a mechanism which cancels the stamp on the letter.

The mechanism for conveying the letters downwardly from behind the plate 29 to the holder 1 includes a shaft 34 rotatably mounted below the front end of chute 27. A roller 35 is fixed on the shaft 34. A resilient blade 36 is wrapped around the roller 35, and has one end projecting upwardly along the guide wall 37. The blade 36 carries at that end a letter-driving plate 38 having a roughened outer surface and a tapered upper end 38a. The shaft 34 is pivoted to and from through a predetermined angle in synchronism with certain other parts of the mechanism to be described later. As the shaft 34 rotates counter-clockwise, the plate 38 moves upwardly behind the forward letter in back of the plate 29. On its return downward movement, the roughened surface, aided by gravity, carries the letter along with it, the letter passing between the plate 38 and a spring loaded roller 39. The extension plate 38 does not move upwardly all the way to the top of the letter, but only engages a portion of the back surface thereof.

On the shaft 34 is fixed an arm 40 to which is pivotally connected a rod 41 extending upwardly and engaging the lower surface of a plate 42 which runs in a channel 43 provided in the guide wall 37. A spring 44 biases the plate 42 downwardly, so that it moves in synchronism with the blade 36 and its extension 38.

Opposite the guide wall 37 and attached to the frame of the machine are a pair of brackets 45, pivotally supporting at their ends a pair of upstanding arms 46 which carry at their upper ends a cross-shaft 47. The cross-shaft 47 has fixed on it a pair of projections 48 which extend toward the plate 42 and also has fixed on it a pair of downwardly extending arms 49 carrying between them a printing roller 50. A spring 51 biases the levers 46 rearwardly, toward a position wherein the projections 48 engage the front of the letter as it moves downwardly, and hold it tightly against the guide wall 37 and the plate 42. When the letter and the upper end of the plate 42 both clear the ends of the projections 48, the channel 43 is open to receive the projections 48. This allows the lever 46 to move counter-clockwise under the influence of the spring 51 so that the printing roller 50 is carried against the face of the letter, thereby cancelling the stamp. The letter continues to move downwardly between rollers 52 pivotally mounted on the brackets 45 and rollers 53 pivotally mounted on arms 54 carried by the shaft 34. After passing between these rollers, the letter drops into a pocket in a holder 1 positioned immediately beneath it.

The path of movement of the blocks 14 and holders 1 through the indexing station will now be described. Referring to Fig. 9, a suitable conveyor (not shown) delivers blocks 14 such as that illustrated in Figs. 4 and 5, filled with empty holders 1, to a receiving location at the top of the indexing station and generally indicated at 55. From the receiving location 55, each block of empty receptacles 30 is moved downwardly by suitable mechanism which is shown and described more completely in my copending application Serial No. 17,984 mentioned above. In its travel through the indexing station, each block 14 moves downwardly intermittently, and stops successively at an unloading location 56, a reloading location 57 and a discharging location 58. Each block moves downwardly from one location to the one below as soon as the lower location is empty, that is to say, when the block previously occupying that station has moved onward. As a block 40 enters location 56, a fixed lug 24 engages the hooked arm 23 on the block and rotates it counter-clockwise sufficiently to unlock the holders carried by the block.

Parallel to the block in its location 56 are a pair of upper conveyor belts 59 and lower conveyor belts 60. The conveyor belts 59 and 60 are grooved or corrugated to receive the upper and lower edges of the rear walls 3 of the holders 1.

The conveyor belts 59 and 60 define between them a storage chamber 61 for empty holders unloaded from a block 14 at location 56. The conveyor belts 60 extend around a pulley 62 (see Fig. 7) and above a third set of grooved conveyor belts 63. The belts 60 and 63 define between them a storage chamber 64 for holders which have been loaded with mail and which have had their indicating elements set to indicate the destination of the mail. The belts 59, 60 and 63 are driven by movement of the holders themselves, by mechanism to be described later. The holders travel with the belts 59, 60 and 63 in the directions indicated by the arrows in Fig. 7. They move forwardly with the belts 59 and 60 until they reach the forward end of chamber 61, at which time they are located laterally between two coding units 201 (see Fig. 6). These coding units are effective by means of mechanism to be described below to set the indicating elements in the sides of each holder as a letter is dropped into the holder from above. After each holder has a letter placed in it and its indicating elements coded, it is moved downwardly to a position at the forward end of the storage chamber 64. It is then pushed rearwardly into the chamber 64. When the chamber 64 is filled, the leading holder in that chamber engages a control switch and starts the operation of a loading and unloading mechanism described below, which transfers the filled holders in the storage chamber 64 to an empty block waiting at location 75 57. On its return movement, this mechanism also ex-

tracts the empty holders from a block waiting at location 56 and transfers them to storage chamber 61 between the grooved belts 59 and 60.

The loading and unloading mechanism (Fig. 9) includes a pair of worms extending horizontally between the storage chambers 61 and 64, one at each end of the machine. One of the worms is shown at 65 (Fig. 9). Threaded on the worms 65 are bridges 66 which connect a pusher 67 normally located alongside the storage chamber 64 and an extracting mechanism 68 normally located alongside the storage chamber 61, in the positions shown in Fig. 9. When the operation of the loading and unloading mechanism is initiated by the filling of storage chamber 64, the worms 65 start to run in a direction to move the bridges 66 to the right as shown in Fig. 9 so that the pusher 67 pushes the loaded holders 1 out from between belts 60 and 63 and into the block 14 waiting at the location 57. As this phase of the movement starts, the storage chamber 61 has been substantially emptied of its receptacles since they have been moved forwardly and filled. The extracting mechanism 68 therefore encounters no receptacles as it moves to the right across the storage chamber 61. When the pusher 67 reaches its extreme right hand position, extractor 68 is engaging the empty holders in the block at location 56. The extractor 68 is provided with a pair of jaws 69 which may be spread and closed by means of a suitable cam or other mechanism (not shown), operated in synchronism with the movement of the loading and unloading mechanism. The jaws 69 are adapted to engage the hooks 9 formed on the holders 1. As the extractor 68 moves to the right, the jaws are spread apart. When the extractor reaches its right hand limit of movement the jaws 69 are moved together and engage the hooks 9. Thereupon the direction of motion of the worms 65 is reversed and bridges 66 are driven to the left. Since the hooks 9 on the holders 1 are then engaged by the jaws 69, the holders are moved out of the block and into the storage chamber 61 between the belts 59 and 60. As the extractor 68 approaches its normal position, the jaws 69 are operated to release the hooks 9 when the holders are in their proper position between the belts 59 and 60. After the extractor 68 reaches its normal position it remains there until its driving mechanism is again actuated by the filling of storage chamber 64.

The downward movement of the filled holders from their position at the forward end of chamber 61 to the position immediately below at the forward end of chamber 64 is accomplished by a pair of vertically extending racks 70 which are moved on suitable guides 71 and are driven by gears 72. Near their upper ends, each of the racks 70 pivotally supports a link 73 whose rotation in a clockwise direction is limited by a suitable stop 74. On the free end of the link 73 is pivotally supported another link 75 carrying a roller 76. As the rack 70 moves downwardly, the roller 76 engages the upper edge of the front wall 2 of the foremost holder 1 and pushes it downwardly. This downward motion continues until the holder reaches the position at the front end of the chamber 64. The gear 72 is then reversed and the rack 70 moves upwardly to engage the next holder. During the upward movement, the roller 76 pivots on its supporting linkage and rolls across the front of the leading holder 1 in the storage chamber 61, holding it frictionally against the holder behind it and preventing it from falling until the rack 70 reaches its uppermost position.

After the holder has moved downwardly to the foremost position in the storage chamber 64, and the rack 70 starts back upwardly, a pusher 80 (see Fig. 7) is operated to push all the holders in storage chamber 64 back one position, so that the foremost position will again be empty when racks 70 bring the next holder down.

If the operator of the machine cannot decipher an address, or if for any other reason he wishes to remove a letter from the classification system, he operates a pedal 77 (Fig. 6) connected through suitable linkage to a pair of

levers 78, which, as shown in Fig. 8, are adapted to engage the upper ends of the opening rods 8 in the foremost holder as it moves downwardly, thereby opening the bottom of that holder so that the letter falls out into a bin 5 79 located at the bottom of the machine.

INDEXING STATION—CODING MECHANISM—
FIGS. 10-16

10 These figures illustrate the complete coding mechanism at the indexing station including the operator's control panel, the preselecting controllers 81 which are actuated from the control panel and the coding units 201 operated by the controllers 81.

15 A control panel is illustrated at 82 in Fig. 10 and includes an insulating plate 83 having spaced parallel channels 84 formed in its upper surface. Between the channels 84 are rows of countersunk holes 85. In each of the channels 84 is located a glass tube 86, which carries suitable destination indicating cards. The glass tubes 86 are held in place in the channels by a cover plate 87, which is provided with windows 88 through which the destination indicating cards may be observed. The cover plate 87 is also provided with holes aligned with the countersunk holes 85 in the plate 83. Each window 88 for viewing the destination indicating cards is aligned with one of the holes 85. Underneath each of the holes is mounted an electric switch 89, shown in detail in Fig. 11. The switch 89 may be actuated by inserting a stylus 90 through the hole 85. Each row of switches 89 is attached to a laterally extending support 92, which is located immediately under the plate 83 and is provided with apertures in its under surface for receiving the switches 89. Each switch 89 is fastened to the support 92 by means of a pin 93. Each switch 89 has a cylindrical body 91 having a central passage closed at its lower end by a plug 94. Within this passage is a sliding rod 95 of insulating material provided at its upper end with a conical tip on which rests a ball 96. The insulating rod 95 carries two vertically spaced electrically conductive rings 97 and 98. A spring 99 biases the rod 95 upwardly, so that the ball 96 rests against the bottom of the countersunk hole 85. Attached to the outside of the body 91 by any suitable means such as an insulating 45 clamping sleeve 100 are a number of contacts 101 which extend through suitable apertures in the body 91 and engage the surface of the rod 95. When the switch is in its normal position as shown in Fig. 11, contacts 101 engage the insulating surface of the rod 95 and no circuit is completed through them. When the switch is operated, by thrusting a stylus through the hole 85 and pushing the rod 95 downward, the ring 97 is moved down into contact with both the contacts 101 and the circuit is completed through them. Although only two contacts 101 are shown in Fig. 11, it will be readily apparent that larger numbers of contacts may be used. Furthermore, additional contacts may be mounted on the switch for cooperation with the ring 98 when the rod 95 is depressed.

50 It is essential that only one of the switches 89 be actuated at one time, for reasons which will become more apparent later. While a simple push-button switch may perform all the switching functions of the switch 89, it will be appreciated that the switches 89 may be operated only by the use of the stylus 90. Therefore, if the operator has only one stylus he can operate only one switch at a time. If other types of switches are used, for example push-button switches, suitable electrical or mechanical interlocking must be provided between the switches to prevent the actuation of more than one switch 55 at any time.

56 Fig. 12 illustrates the electrical circuits controlled by the switches 89. Only four such switches are shown in Fig. 12, numbered respectively 89a, 89b, 89c and 89d. The circuits controlled by these four switches are intended 76 only as representative of the possible circuits. It will be

readily recognized that there are a very large number of electromagnet combinations which may be connected for energization by a correspondingly large number of switches.

In Fig. 12 the switches 89 control the selective energization of a set of thirty-three electromagnets, arranged in eleven rows and three columns. Each electromagnet is assigned the reference numeral 102, with an added hyphenated designation indicating the row and column of the electromagnet. Each row has a numerical designation and each column an alphabetical designation. For reasons to be pointed out below, each switch 89 must, when actuated, cause the energization of one electromagnet in each column, but it must not cause the energization of more than one electromagnet in one row.

In the circuit shown, electrical energy is supplied by a battery 103. Switch 89a controls a circuit for energizing electromagnets 102-1a, 102-2b, and 102-3c. The switch 89b controls a circuit for energizing electromagnets 102-4c, 102-5b, and 102-6a. Switch 89c controls a circuit for energizing electromagnets 102-6a, 102-7b and 102-8c. Switch 89d controls a circuit for energizing electromagnet 102-9c, 102-10a and 102-11b. Each electromagnet may be included in the circuits controlled by several different switches, as is the case with the electromagnet 102-6a.

As will be pointed out below, each row of electromagnets controls the positioning of one of the eleven indicating elements carried by the holder. The three electromagnets in each row respectively determine different indicating positions to which that indicating element may be moved.

The electromagnets 102 are all located within a controller 81 shown in detail in Fig. 13. In this figure, most of the electromagnets have been omitted in order to clarify the drawing. The mechanism of this controller is more completely described and claimed in my U. S. Patent No. 2,469,035 issued May 3, 1949.

Referring to Figure 13, the controller 81 is shown as enclosed within an elongated cylindrical casing. A shaft 104 extends through the center of this casing and is continuously rotated by any suitable means, being provided with a pulley 105 for that purpose. Rotatably and slidably mounted on the shaft 104 are three disks 106, 107 and 108. These disks are driven from the shaft 104 through friction clutches generally indicated by the reference numeral 109. In the case of the disc 108, the friction clutch 109 includes a friction disk 110 fixed on the shaft 104, another friction disk 111 keyed to the shaft 104 so that it rotates with it but is slideable along it and a coil spring 112 encircling the shaft 104 and biasing the friction disk 111 into engagement with disk 108 and urging the latter disk into engagement with the friction disk 110. Each disk 106, 107 and 108 has on its periphery one or more lugs 113. Adjacent each of the lugs 113 on the left hand side of the respective disks as they appear in Fig. 13 is an axially extending finger 114, provided with a notch 114a near its extremity.

At the left of each of the disks 106, 107 and 108, as they appear in Fig. 13, is mounted a stationary annular bank of electromagnets 102. Each bank of electromagnets corresponds to one of the vertical columns of electromagnets 102 appearing in Fig. 12. The banks appearing at the left of disks 106, 107 and 108 will be hereinafter respectively referred to as A, B and C banks.

Each of the electromagnets 102 includes an armature 115, spring biased to an inactive position, shown in dotted lines in the case of electromagnet 102-1a in Fig. 13, and movable to an active position, shown in full lines for said electromagnet 102-1a, wherein a lug 116 carried by the armature 115, projects into the path of the finger 114 carried by the associated disk. Each lug 116 is provided with a rib 116a which is adapted to engage the notch 114a in the finger 114.

It may be seen that upon energization of any of the

electromagnets, the associated disk will be stopped from rotation when during the next revolution of the disk, the finger 114 on the disk engages the lug 116. Furthermore, because of the engagement of the rib 116a in the notch

114a, the biasing spring in the electromagnet will not be effective to restore the armature 115 to its inactive position. On the contrary, once the armature has been moved to its active position, it will be latched there by the engagement of the rib and notch until additional steps are taken 10 to disengage the rib and notch as pointed out below. Consequently, energization of any one electromagnet causes a selected one of the disks to be stopped in a predetermined angular position.

Around the periphery of the cylindrical casing of the controller 81 are mounted a number of push rods 117 (see Figs. 13-14). There are eleven electromagnets 102 in each of the three banks, and there are eleven push rods 117. Each push rod is longitudinally slideable in the controller 81. The push rods are biased by suitable springs 20 (not shown) to the position shown in Fig. 13. Each push rod 117 is provided with a series of three projecting lugs 117a, 117b and 117c. These lugs project radially inwardly of the controller 81 and are adapted to be engaged at times by the lugs 113 on the peripheries of the disks 25 106, 107 and 108. When the rods 117 are in their normal positions, the spacing between the lug 117a and the lug 113 is a predetermined distance indicated by the reference character *a* in the drawing. Similarly, the spacing between lug 117b and the lug 113 is a different distance *b*, 30 smaller than *a*. Likewise, the spacing between lug 117c and lug 113 is a still smaller distance indicated at *c*.

The shaft 104 may be translated endwise of the controller 81 by means of a lever 118a located outside the casing and acting on a push rod 119a which extends into 35 the casing and engages a flange 120a formed on one end of the shaft 104. A spring 134 biases the shaft 104 endwise to the normal position shown in the drawing.

When any of the discs 106, 107 or 108 are stopped from rotation by activation of the associated electromagnet 40 102, the lug 113 is positioned in alignment with but spaced from its associated lug 117a, 117b or 117c along the longitudinal axis of rod 117. Thereafter, any movement of a disc by moving shaft 104 along its longitudinal axis will cause endwise movement of rod 117 through the 45 respective disc and rod lugs after the associated space *a*, *b* or *c* has been spanned. The distance through which the rod 117 is translated is determined by the particular bank in which the energized electromagnet is located. If the electromagnet is in A bank then the lug 113 must 50 travel through the distance *a* before it engages the lug 117a to drive rod 117 so that the distance through which the rod 117 is moved is relatively short. If the electromagnet is in the B bank the lug 113 only has to travel through the smaller distance *b* before engaging the lug 55 117b, so that the rod 117 is moved through a greater distance. Similarly, energization of an electromagnet in the C bank results in a translation of the rod 117 through a still greater distance.

When the disks 106, 107 and 108 are translated by 60 longitudinal shifting of the shaft 104, the notches 114a are moved out of engagement with the ribs 116a. In order that this disengagement will not result in the immediate rotation of the disks, the lugs 117a, 117b and 117c and the lugs 113 are formed with interengaging faces. These faces are formed so that they engage sufficiently 65 to prevent rotation of the disks before the ribs 116a and notches 114a have disengaged sufficiently to permit such rotation, even though additional translation of the disks must take place before the rods are translated endwise by the engagement of the lugs.

The movements of the respective rods 117 are transmitted through bell crank levers 118 to vertically extending push rods 119, each carrying a rack 120 (Fig. 16) which cooperates with a pinion 121 formed on a coding 70 75 or setting tool 122. There are eleven bell crank levers

118, push rods 119 and coding tools 121, corresponding to the eleven electromagnets in each of the three banks and to the eleven indicating elements carried by each of the holders 1.

All three of the disks 106, 107 and 108 must be stopped each time that the rod 119 is translated, because one disk left rotating would, upon translation of rod 119, have its lug 113 engage one of the lugs on one of the rods 117 at random, thereby producing an erroneous code setting. For that reason, one electromagnet in each of the three banks A, B and C, must be energized whenever each of the switches 89 is actuated. It may also be seen that the switches 89 must never energize two electromagnets in the same bank at the same time, because the disks 106, 107 and 108 can stop only in one angular position.

If in a particular system it were required to have more code combinations available, the controller 81 could be expanded, for example, by having six disks and six banks of electromagnets. It would then be possible to preselect two rods 117 for translation through distance *a*, two for translation through distance *b*, and two for translation through distance *c*. While the arrangement shown in the drawings only permits $11 \times 10 \times 9 = 990$ classifications, the arrangement described just above would permit $11 \times 10 \times 9 \times 8 \times 7 \times 6 = 332,640$ classifications.

Referring to Fig. 14, it may be seen that the coding or setting tools 122 are mounted for horizontal translation and for rotation in a frame 123. The frame 123 also guides the vertical movement of the push rods 119. Each setting tool 122 is provided at its right hand end with a slot 122a adapted to engage and receive the rib 12b on one of the indicating elements 12 of a holder 1. The setting tools 122 are biased by springs 124 to normal positions, shown in Fig. 14, where their slotted ends 122a are recessed within the frame 123. A pusher bar 125 is provided for simultaneously engaging the opposite ends of the setting tools 122 and moving them to the right against their respective springs 124 to active positions in which their slotted ends 122a project from the frame 123 so that they engage any indicating elements 12 which are aligned with them, and push those elements inwardly far enough to free the ends of the ribs 12b from the notches 11b.

The pusher bar 125 is provided with a central projection 126 which extends through the frame 123 and has a tapered end adapted to engage a fitting tapered recess 5a formed in the lateral wall of the holder 1. Engagement of the projection 126 and the tapered recess 5a brings all the elements on the holder 1 into alignment with the setting tools 122 so that the indicating elements are not affected by transverse forces tending to make them bind in their respective recesses.

The pusher 125 is driven by a rod 126 whose movements are coordinated with the mechanism for advancing the holders and with the mechanism for energizing the electromagnets.

As the holders 1 approach the coding mechanism 201, their indicating elements have a random orientation, depending upon the particular code in which they were last set. In order that a new code may be accurately established by the setting tools 122, it is necessary that the indicating elements first be restored to a predetermined neutral position, for example one in which their ribs are vertical. This operation of setting the indicating elements in a neutral position is hereinafter referred to as a decoding operation. The mechanism for performing the decoding operation is illustrated in Figs. 15 and 16. Referring to Fig. 16 it may be seen that the endwise translation of shaft 104 is transmitted through a bell crank lever 128 to a push rod 129 which extends upwardly through the frame 123 and carries an elongated rack 130 for engaging pinions 131a carried by each of a set of eleven decoding tools 131. The decoding tools 131 are similar in structure to the setting tools 122, the principal differ-

ence being that they are all operated by the rack 130 instead of being operated by individual racks 121.

The decoding tools 130 and the setting tools 122 are located side by side along the path of movement of the holders 1. When one holder is aligned with the setting tools 122, the holder immediately behind it is aligned with the decoding tools 131. At the same time that the setting tools are actuated to move preselected indicating elements through preselected angles, the decoding tools 131 are actuated to set the indicating elements on the following holder 1 in the same angular positions.

When the decoding tools engage the end of an indicating element 12 whose rib 12b is not in alignment with the slotted end 131a of the decoding tools, then during the first part of the rotation of the decoding tool 131, the indicating element 12 will not move angularly since there is not sufficient friction between the end of the rib and the end of the tool 131 to cause the element to follow the tool. As soon as the rib becomes aligned with the slot in the decoding tool 131, the tool will move endwise into full engagement with the indicating element, and the element will thereafter turn with the setting tool until the rotation of the tool is completed. All the decoding tools are set in the same angular positions, and are rotated through the same angle. In the structure shown, this angle is preferably 180° . In any event, it must be larger than the range of angles used in the code. Consequently, it may be seen that regardless of the angular position of the elements 12 when they move into alignment with the decoding tools 131, they are all in the same angular position when they leave the decoding tools to move into alignment with the coding tools.

INDEXING STATION.—SEQUENCE OF OPERATION

When an operator observes a letter at the indexing station he first actuates one of the switches 89 in accordance with the destination of the letter. This preselects the coding tools to be rotated and their angles of rotation. He then actuates a lever 133 (Fig. 6) which starts a driving mechanism actuating the rod 127 to operate the pusher bar 125 to drive the decoding and coding tools into engagement with the indicator elements aligned therewith. After the pusher 125 has moved the setting tools 122 and the decoding tools 131 into engagement with the indicating elements, the shaft 104 is shifted endwise to rotate the preselected setting tools and all the decoding tools. As soon as this motion is complete, the pusher 125 is reversed to disengage the tools from the indicating elements and the rod 104 is returned to its normal position by the spring 134. At the same time that this operation of the pusher 125 and of the rod 104 is taking place, the shaft 34 (Figs. 7 and 8) is being oscillated to drop the letter into the holder 1 whose code indicating elements are being set.

As soon as these operations are complete the pusher 80 (Fig. 7) is actuated to force the previously filled holders 1 back into the receiving chamber 64, thereby driving the belts 60 and 63 to bring the decoded holder into line with the coding tools and to bring another holder having a random code into line with the decoding tools. At this time also, the operator is free to actuate one of the switches 89 in accordance with the destination of a new letter which has been brought into view by the dropping of the first letter into the holder 1. As soon as the new holders are brought into line with the coding and decoding tools, the operator may again actuate the lever 133.

The pusher 80 is then retracted and the racks 70 become effective to lower the holder carrying the letter into position in front of the storage chamber 64. The racks 70 are then restored to their upper positions ready to carry the next holder down as soon as it has received a letter and its engaging elements have been set or coded.

While only one coding mechanism 201 and its associated controller 81 has been described, it should be noted that two such units are preferably provided, as shown in Fig. 6, and that the holders are provided with two sets of indicating elements on their opposite sides. The purpose of this double coding arrangement is to simplify the structure required at the pre-sorting and final sorting stations, described below.

FIGS. 17-20.—PRE-SORTING STATION

A pre-sorting station is an apparatus which receives blocks of filled and coded holders from the indexing station, the holders having their indicating elements set in random codes depending upon the random order in which the letters were received at the indexing station. The pre-sorting station includes extracting mechanism which removes the holders from the blocks in groups, each group being characterized by a common distinctive code. These groups are reassembled and again loaded into blocks, each block now containing only holders having the same distinctive code. The blocks so loaded are then transferred to a final sorting station. In a large installation, the holders leaving the first pre-sorting station may then pass through a second, or more pre-sorting stations before reaching a final sorting station.

Figs. 17 and 18 illustrate one stage of a presorting station in which all the holders bearing one distinctive code are removed from an entering block and reassembled as a compact group and loaded into an empty block to be conveyed to the final sorting station.

Referring to Fig. 17, a block loaded with receptacles enters this stage of the pre-sorting station, which is illustrated as being the first stage, at the location 135. In a typical installation a series of these stages are located one above the other and the blocks which are being selectively unloaded move vertically from one stage to the next. Alongside the block when it rests at an unloading location such as the location 135, are a pair of vertically spaced horizontal conveyor belts 136 and 137, defining between them a receiving chamber 140. These conveyor belts are similar in structure to the grooved or corrugated conveyor belts 59, 60 and 63 at the indexing station. An extracting mechanism 138 has a normal position as illustrated in the drawing, and is threadedly supported at its ends on a pair of worms 139. When the worms are driven, the extracting mechanism 138 moves horizontally through the receiving chamber 140 between the conveyor belts and approaches the side of the block 14 stopped at location 135. The extracting mechanism 138, as described more fully below, includes a plurality of parallel code sensing devices 141, one for each holder 1 in the block 14. Each code sensing mechanism 141 is associated with a pair of extracting jaws 142 which are adapted to engage the hooks 9 on the holders 1. As the extracting mechanism 138 approaches the block 14, the extracting jaws of the several code sensing devices 141 are spread so that they do not engage the hooks 9. Each code sensing mechanism engages the code indicating elements on the side of a holder 1. If the code indicated by the elements on the holder 1 is the same as the code for which the sensing mechanism 141 has been set, then the jaws 142 are actuated to engage the hooks 9.

The code sensing mechanisms 141 at any given stage of the pre-sorting station are all set for the same characteristic code which may be the code setting of one indicating element only, or alternatively it may be a combination of settings. They are all actuated simultaneously to close their jaws on all holders in the block which bear that code. The worms 139 are then reversed and the extracting mechanism 138 travels outwardly through the chamber 140 carrying with it the receptacles 1 which have been identified as bearing the code in question. Nearer the outer position of the extracting mechanism, the jaws 142

65 70 75

are actuated to release their respective holders, leaving the selected holders between the conveyor belts 136 and 137. The conveyor belts then start up and move the selected holders to the right as shown in the drawing, transferring them onto a stationary bridge 143. Each holder is moved across the bridge 143 only by being pushed by a holder behind it. Consequently, the holders 1 which rest between the conveyors 136 and 137 with a random spacing are compacted into a solid stack as they are moved onto and across the bridge 143. Holders leaving the bridge 143 pass on to another set of conveyor belts 144 and 145, which also are driven only by the motion of the holders. They pass from the conveyors 144 and 145 across another stationary bridge 146 into a loading compartment generally indicated at 147 where they are supported on another set of conveyor belts 148 and 149. Alongside the chamber 147 is a location 147a which receives empty blocks which have had all their holders removed by passage through a series of pre-sorting stages whose extracting mechanisms are set for codes which cumulatively are effective to remove all the holders from the blocks. When an empty block is waiting at location 147a and the chamber 147 is filled with holders, a pair of worms 150 are actuated to drive a pusher mechanism 151 to push the holders in the chamber 147 laterally into the waiting block at location 148. That block is then removed by suitable conveyor mechanism to a final indexing station.

Although in the mechanism illustrated, holders are withdrawn from one side only of the block at location 135, another extracting mechanism 138 may be provided on the opposite side of location 135, so that two groups of holders, each group bearing a different code, may be simultaneously removed from a block stopped at a single pre-sorting stage. The blocks 14 are open at both sides, and the holders 1 carry code indicating elements at both sides, so that such a dual extracting arrangement can be used.

The conveyor mechanism between location 57 of the indexing station and location 135 of the pre-sorting station is hereinafter referred to as "trunk conveyor means," and the conveyor mechanism between receiving stations such as 140 and the final sorting stations is hereinafter referred to as "branch conveyor means." The particular conveyor mechanism shown herein may be replaced by equivalent mechanism, since the particular conveyor does not form a necessary part of the invention claimed herein.

The construction of one of the code sensing mechanisms 141 is illustrated in Figs. 19 and 20. The mechanism 141 has a vertically elongated body 152 having a central vertically extending recess 153 along the front thereof, as it appears in Fig. 19, and separating the body into a front wall portion 152a and a back wall portion 152b. The body 152 is provided with eleven horizontal bores 154 corresponding to the eleven code indicating elements carried by the holders 1. These bores 154 extend completely through the front wall 152a and into the back wall 152b, where they terminate in blind ends.

In certain of the bores 154, there are provided code sensing tools 155. The number of tools 155 corresponds to the number of active code indicating elements 12 in the particular code on which the particular sorting operation is based. It may include all, or only a part, of the indicating elements used in the complete code classification. In the drawings, there are shown three code sensing elements 155. Each element 155 has a slot 155a in its outer end. In the drawings, all these slots 155a are shown as being horizontal, although they may have other angular positions corresponding to any of the several angular positions in which the code indicating elements 12 may be set. A spring 156 is located behind each of the code sensing tools 155 and biases it outwardly so that the end bearing the slot 155a normally projects from the bore 154. A pin 157 extends transversely of the bore 154 through the wall 152a and a slot 155b in the code sensing

tool 155. The pin 157 limits the forward movement of the tool 155 under the influence of the spring 156.

The back end of each of the elements 155 is provided with a vertical slot 155c (Fig. 20) adapted to receive one of a pair of bars 158, 159, which move vertically in the recess 153. Each code sensing tool 155 is provided with a recess 155d extending transversely of either its upper or lower surface, depending upon whether the particular tool 155 straddles bar 158 or 159.

The bars 158 and 159 together carry eleven pins 160, corresponding to the eleven code indicating elements on the holders 1. The bars 158 and 159 are attached at the upper and lower ends respectively, of the code sensing mechanism 141 to the jaws 142. At their inner ends the bars 158 and 159 are cut away so that their ends extend past each other. The projecting inner ends of the bars 158 and 159 carry pins 161 which ride in a slot 162 formed in a disk 163. This arrangement, including the pins 161 and the slotted disk 163, is effective to move the upper bar 158 downwardly whenever the lower bar 159 is moved upwardly so that the jaws 142 open and close together.

The disk 163 rotates 90° when the jaws 142 are moved between their open and closed positions. The disk 163 is provided with a pair of V-shaped notches 163a and 163b, spaced 90° apart and adapted to engage a V-shaped spring 164 by which the disk 163 is maintained in either of its two extreme positions.

The wall 152a of the code sensing mechanism is provided with a central tapered projection 152c which engages the correspondingly tapered recess 5a in the wall of the holder 1 whose code is being sensed. The wall 152a is also provided with a guiding flange 165 which enters between adjacent holders as the code sensing mechanism is moved into engagement with the holders. This guiding flange and the cooperating guiding surfaces of the projection 152c and recess 5a ensure that the code sensing tools 155 are aligned with the code indicating elements 12 carried by the holder 1.

If the slots 155a in the ends of the code sensing tools 155 are set at the same angles as the code indicating elements with which they are aligned, then the respective code sensing tools 155 are not shifted endwise in their bores 154 by the movement of the code sensing mechanism 141 against a holder 1. Under such conditions, the recesses 155d in the several code sensing tools remain aligned with the pins 160 carried by the bars 158. When the code sensing mechanism reaches its sensing position, shown in Fig. 19, it is above a shaft 166 carrying an arm 167 provided with a spring finger 168. After the code sensing mechanism reaches the position shown, the shaft 166 is rotated clockwise from the position illustrated in Fig. 19, so that the spring finger 168 engages the jaw 142 at the bottom of the code sensing mechanism and tends to drive it upwardly. If the recesses 155d are all aligned with the pins 160 on the bars 158, then the bars are free to move sufficiently to move both the jaws to their closed positions, and are retained there by the engagement of spring 164 with the recess 163a. Then when the code sensing mechanism is retracted or moved to the right as viewed in Fig. 19, the hooks 9 on the holder 1 are engaged by the jaws 142 and the holder 1 is drawn with the code sensing mechanism outwardly from the block 14 in which it has been transported and into the chamber 140 between the conveyor belts 136 and 137.

If, however, any one of the slots 155a in the ends of the code sensing tools does not correspond in its angular position to the angular position of the rib on the aligned code indicating element, then that code sensing tool is forced back into its bore 154 against the spring 157, and its recess 155d passes out of alignment with the adjacent pin 160 on the bar 158. Consequently, when the shaft 166 is rotated, the spring 168 cannot force the jaws 142

to their closed position, but instead is itself forced back against the arm 167. Consequently the jaws do not move to their closed positions but remain open, so that when the code sensing mechanism 141 is retracted, the holder 1 does not follow it but remains in the block 14.

The disk 163 carries an arm 163c, which is in the full line position shown in Fig. 19 when the jaws 142 are open, and in the dotted line position when the jaws are closed.

When the sensing mechanism 141 is being retracted with the jaws closed, then as it nears the end of its travel, a bar 169, associated with all the sensing mechanisms 141 in the extracting mechanism 138, is lowered and pushes the arm 163c from its dotted line to its full line position. This rotates the disk 163 and shifts the bars 158 to open the jaws 142. The holder 1 is thereby disengaged from the sensing mechanism 141 in the chamber 140 between the conveyor belts 136 and 137.

FIGS. 21-25.—FINAL SORTING STATION

Figs. 21 and 22 are respectively a horizontal cross-sectional view and a perspective view, both somewhat diagrammatic, of a single stage in a final sorting station. These figures are similar to Figs. 17 and 18 which illustrate a pre-sorting station.

A final sorting station receives blocks of holders which have already been partially sorted, but which require a final sorting. For example, in a mail sorting system, the 30 holders reaching a final sorting station may all have been classified as containing mail directed to a single state. In the final sorting station, the holders may be separated into groups according to a classification system based on the cities and towns in that state. The final sorting station is effective to empty all the holders it receives into bins corresponding to the destinations of the letters.

Figs. 21 and 22 illustrate a single stage of a final sorting station. The blocks 14 enter this stage at a location 40 170 and may move successively through several such stages, preferably located one above the other. At location 170, some of the holders in the block are extracted from it by an extracting mechanism 138', which is similar to that described in connection with Figs. 17 and 18, and will not be further described. The holders extracted by the mechanism 138' travel as in Figs. 17 and 18, along conveyor belts 136' and 137' to another set of conveyor belts 144' and 145' and thence to a final set of conveyor belts 148' and 149'.

The space between the conveyor belts 148' and 149' is subdivided into three locations, 171, 172 and 173. Alongside the conveyor belts 148' and 149' in location 50 171 is a code sensing and holder emptying mechanism illustrated in Fig. 23 and indicated generally by the reference numeral 174.

Below the belt 149' in location 171 is a number of chutes 175, forming portions of letter receiving bins. The mechanism 174 includes a plurality of code sensing and holder emptying units 176, one of which is illustrated in detail in Fig. 24.

Each code sensing unit 176 is generally similar to the code sensing unit 141 illustrated in Figs. 19 and 20. It includes one or more code sensing tools 155' whose structure and function is the same as tools 155 of Figs. 19 and 20. Instead of two oppositely moving bars 158, 159, as in Figs. 19 and 20, the code sensing mechanism 176 has a single central bar 177, whose upper end is cut away on the side nearest the holder 1, as illustrated at 177a.

Above each holder 1 at the position where it is engaged by a code sensing unit 176, is supported a bar 178, which is laterally shiftable in a stationary frame 179'. The bar 178 carries a vertical guide 180 for a vertically shiftable rack 181 which at times engages a pinion 182 fixed on a rotatable but laterally stationary shaft 183. The right hand end of bar 178, as it appears in Fig. 24,

is adapted to engage the bar 177 of the code sensing mechanism. The left end of the bar 178 is provided with a slot 178a which receives a pin 179 mounted on a pivoted disk 180'. The disk 180' also carries a diametrically opposite pin 179' which moves in a slot in a similar bar 178' forming part of a similar mechanism at the opposite side of the holder 1.

The bar 178 is biased to the position shown in the drawing by a spring 184 attached to the frame 178. In this position, the rack 181 engages the pinion 182. After 10 a holder 1 is moved into alignment with the code sensing unit 176, the unit 176 is moved laterally to the left as viewed in Fig. 24, toward the holder 1, by means of racks 182' (see Fig. 23) formed on the lower stationary side of a frame member 183' which supports all the code 15 sensing units 176. These racks 182' cooperate with pinions 184' fixed on a shaft 185 driven by a motor 186 through a suitable mechanical connection.

As the unit 176 approaches the holder 1, the upper end of bar 177 is engaged by a leaf spring 187, which tends to force the bar 177 downwardly. If the code setting of the indicating elements 12 carried by the holder 1 is the same as that of the sensing tools 155', then the bar 177 is free to move downwardly until the pins 188 carried by it reach the bottom of the notches 155d' in the upper surfaces of the code sensing tools 155'. This downward movement of the bar 177 is sufficient to move the cut-away portion of 177a of the bar 177 into alignment with the end of the bar 178, so that the latter bar remains in its position when the rack 181 engages the pinion 182. 20 Pinion 182 is then rotated to move the rack 181 downwardly. The lower end of rack 181 engages the flange 8a at the upper end of the opening rod 8 in the holder 1 and moves the rod 8 downwardly to open the bottom of the holder and allow the letter therein to fall out into the chute 175 from which it passes into a receiving bin. After the holder has been opened, the pinion 182 is reversed and the rack 181 is retracted so as to be free of the holder 1. The code sensing unit 176 is then withdrawn from engagement with the holder, which passes 30 on to the location 172, where it is stopped and engaged by a holder closing mechanism illustrated in Fig. 25.

The holder closing mechanism includes a vertically movable rack bar 189 which pivotally carries a lever 190 having its lower end bent over to form a hook 191. The rack 189 is reciprocated vertically by a pinion 192 which may be fixed on the same driving shaft 183 as the pinion 182 of Fig. 24.

The parts are shown in the drawing in their inactive positions. The upper end of lever 190 is biased by a spring 193 against the surface of a slide 194. The rack bar 189 is above the opening rod 8 of a holder 1. That opening rod 8 is in its open position.

To close the holder, the pinion 192 rotates counter-clockwise driving the rack bar 189 downwardly. During this downward movement the upper end of lever 189 moves along the surface of the slide 194. When the hook 191 reaches a point just below the flange 8a on the upper end of the opening rod 8, the upper end of lever 190 encounters a boss 195, which causes the lever 190 to turn counter-clockwise against the spring 193 and thereby moves the hook 191 under the flange 8a.

The pinion 192 now reverses and drives the rack bar 189 upwardly. At this time the upper end of the rack bar pushes the slide 194 up with it, so that it retains its angular position with the hook 191 engaging the flange 8a. The opening rod 8 is thereby moved upwardly to its closed position whereupon the motion of the slide 194 is stopped by engagement of a projection 194a on it with a stationary abutment 196. Further movement of the rack bar 189 upwardly causes the lever 190 to return to its normal angular position under the influence of the spring 193, whereupon the hook 191 is freed from the flange 8a. The rack bar 189 continues to move upwardly until it and hook 191 are free of the holder 1.

The holder 1 then moves on to the location 173, where

it encounters a pusher mechanism, which may be similar to the pusher mechanism 151 of Figs. 17 and 18, which transfers the empty holder from the conveyor belts 148' and 149' laterally into an empty block or to another conveyor 5 mechanism which carries the holders to such a block.

The movement of the holders 1 through the locations 171, 172 and 173 must be controlled in accordance with the number of chutes under the conveyor belt 149' at location 171. For example, there may be only one chute opening under the location 171, which may be long enough in the direction of motion of the holders so that ten holders can be supported above it. In that case, the holders may be moved into location 171 ten at a time and may be removed from station 171 in the same quantities. Furthermore, in that case the classifications of all the holders reaching the location 171 must have been determined to be the same by the previous code sensing mechanisms, and the code sensing mechanisms at location 171 can be omitted, with only simple rack and pinion opening mechanisms being provided there.

Alternatively there may be five separate chutes opening under the location 171, in which case the holders approaching that location may have any one of five different classifications. If there are ten code sensing units, as 25 shown in Fig. 23, then two code sensing units are above each one of the five chutes and are set to sense the code of that chute. In that case, the holders must enter the location 171 in pairs and must move forward in pairs, so that each holder will be checked by a code sensing mechanism for each of the five codes before it passes out of the station 171.

What I claim is:

1. Apparatus for sorting articles, comprising a plurality of portable indicating holders for receiving individual articles; a plurality of indicating elements permanently carried by each said holder, each said element being individually settable in a plurality of indicating positions; an indexing station including means operable to place an article in each holder and means operable to set the indicating elements on each holder to indicate one of a plurality of classes in which the article placed therein is classified; a plurality of receiving bins, one for each such class; conveyor means for said holders extending from said indexing station to said receiving bins and including 35 trunk conveyor means leading from said indexing station and a plurality of branch conveyor means having junctions with said trunk conveyor means and leading therefrom to said receiving bins, means at each junction to sense the settings of the indicating elements on the 45 holders, means including said sensing means to selectively transfer the holders from the trunk conveyor means to the branch conveyor means in accordance with their respective classifications, said direction selecting means being effective to direct all the holders of the respective 50 classifications toward their respective receiving bins; and 55 means adjacent each bin to deliver the articles from the holders of its classification into said bin.

2. Apparatus for sorting articles as defined in claim 1, in which said holders include pockets open at the top to receive said articles; said article placing means includes 60 means operable to drop articles by gravity into the open tops of the holders; and said trunk and branch conveyor means include means effective to maintain said holders upright at all times.

3. Apparatus for sorting articles as defined in claim 2, in which said holders have openable bottoms; said bins are located below said branch conveyor means; and said 65 delivering means includes means operable to open said bottoms when said holders are above said bins so that the articles fall by gravity into the bins.

4. Apparatus for sorting articles as defined in claim 1, in which at least one of said branch conveyor means extends past a plurality of bins, and said article delivering means associated with said one branch conveyor means 70 includes additional sensing means at each of said plurality 75

of bins and is effective to deliver to each such bin only articles from holders bearing the classification of that bin.

5. In apparatus for sorting articles, a plurality of portable indicating holders for receiving individual articles, a plurality of individually settable indicating elements carried in recesses in each said holder, each said element being translatable in its recess between an outer indicating position in which it is locked against rotation and an inner setting position in which it is rotatable between a plurality of angular positions, means yieldably holding said elements in their indicating positions; a plurality of setting tools, one for each indicating element on a holder, means for moving said holders successively into a position wherein their indicating elements are axially aligned with said setting tools, said setting tools and said indicating elements having on their aligned ends cooperating transverse ribs and grooves which intermesh only when angularly aligned and effective when intermeshed to cause the elements to follow the angular movements of the tools; means supporting said setting tools for translation and rotation, said tools being translatable with respect to said supporting means between an inactive position wherein said end portions are recessed in said supporting means and an active position wherein said end portions project from said supporting means, means biasing said tools to said inactive position, means operable to move all the setting tools simultaneously to active positions wherein said end portions engage the elements in a holder aligned therewith and move said elements inwardly of the recesses to their setting positions, means operable to pre-select certain of said tools to be rotated and certain angles through which the preselected tools are to be rotated, means operable after movement of the tools to their active positions to rotate said preselected tools through said pre-selected angles to rotate the particular elements engaged by said preselected tools, so that said non-circular end portions of said particular elements present a preselected code indication, and means operable thereafter to retract the tools to their inactive positions.

6. In apparatus for sorting articles, a plurality of portable indicating holders for receiving individual articles, a plurality of individually settable indicating elements carried in recesses in each said holder, each said element being translatable in its recess between an outer indicating position in which it is locked against rotation and an inner setting position in which it is rotatable between a plurality of angular positions, means yieldably holding said elements in their indicating positions; decoding mechanism including a plurality of decoding tools, one for each indicating element on a holder, means for moving said holders successively into a position wherein their indicating elements are aligned with said decoding tools, said tools and said indicating elements having on their aligned ends cooperating transverse ribs and grooves terminating in plane end surfaces perpendicular to the tool and element axes, said ribs and grooves intermeshing only when angularly aligned and effective when intermeshed to cause the elements to follow the angular movements of the tools, said plane end surfaces being slidable on each other when the ribs and grooves are not intermeshed so that the tools may move relative to the elements to bring the ribs and grooves into angular alignment; means supporting said tools for translation and rotation, said tools being translatable with respect to said supporting means between an inactive position wherein their element engaging portions are recessed in said supporting means and an active position wherein said portions project from said supporting means, means biasing said tools to said inactive position, means operable to move all the tools simultaneously to active positions wherein said end portions engage the elements in a holder aligned therewith and move said elements inwardly of the recesses to their setting positions, said tools all having the same angular position, means operable after movement of the tools to their active positions to rotate all said tools through an

angle large enough to include all the angular positions in which the elements may be set, so that the elements are all intermeshed with their aligned tools and moved to corresponding angular positions, and means operable thereafter to retract the tools to their inactive positions.

7. In apparatus for sorting articles, a plurality of detached portable indicating holders for receiving individual articles, a plurality of indicating elements permanently carried by each said holder, each said element being individually settable in a plurality of indicating positions; an indexing station including means to advance a plurality of articles one by one to a viewing position wherein they are visible to an operator; mechanical means operable by the operator to preselect one of a plurality of classes in which the article at the viewing station is to be classified; mechanical means operable by the operator after said one class is preselected to move the article from the viewing station to one of said holders and to set the indicating elements of said one holder to indicate said preselected class in accordance with an established code.

8. Apparatus for indexing articles as defined in claim 7, in which said holders have pockets open at the top for receiving said articles and including means for moving said holders successively to a coding location below said viewing position, said article moving means being aided by gravity in moving each article from the viewing position to a holder at the coding location.

9. In apparatus for sorting articles, a holder for receiving an article, a plurality of indicating elements carried in recesses in said holder, each said element being individually settable in its recess in a plurality of indicating positions, said holder having a positioning surface in a fixed spatial relationship with respect to said recesses, code sensing mechanism including a plurality of axially movable tools having working ends adapted to engage said indicating elements, a guide member connected to the tools for concurrent movement therewith toward and away from the holder, said guide member having a positioning surface fixed in the same spatial relationship with respect to said tool axes that the positioning surface on the holder has with respect to said recesses, said positioning surface on the guide member being adapted to matingly engage the positioning surface on the holder, and means operable to move said tools and the positioning surface on the guide member into cooperative engagement with said indicating elements and the positioning surface on the holder, respectively.

10. In apparatus for sorting articles, a holder for receiving an article, a plurality of indicating elements carried in recesses in said holder, each said element being individually settable in its recess in a plurality of indicating positions, said holder having a positioning surface in a fixed spatial relationship with respect to said recesses, code sensing mechanism including a plurality of axially movable tools having working ends adapted to engage said indicating elements, a guide member connected to the tools for concurrent movement therewith toward and away from the holder, said guide member having a positioning surface fixed in the same spatial relationship with respect to said tool axes that the positioning surface on the holder has with respect to said recesses, said positioning surface on the guide member being adapted to matingly engage the positioning surface on the holder, means operable to move said tools and the positioning surface on the guide member into cooperative engagement with said indicating elements and the positioning surface on the holder, respectively, and means operable to rotate said tools while they engage said elements to change the angular positions of the elements.

11. Apparatus for sorting articles as defined in claim 9, in which said tools and said elements have on their axially aligned ends cooperating transverse ribs and grooves which intermesh only when angularly aligned,

and including a support for said tools, spring means biasing said tools to a normal position in which said working ends project from said support, said tools being movable inwardly of said support against said spring means, said tools having apertures therein spaced from said working ends, a bar movable transversely of said tools and carrying pins aligned with said apertures when said tools are in their normal positions, resilient means operable to move said bar transversely of said tools, said tools being effective when moved inwardly of said support to move their apertures out of alignment with said pins and block transverse movement of said bar, said elements being effective when said positioning surfaces are in engagement to move said tools inwardly of the support if said axially aligned ends of the tools and elements are not also angularly aligned and ineffective to move the tools inwardly if the ends of the tools and elements are angularly aligned, and means operable after movement of the support into engagement with the holder to drive said resilient means, and a control device connected to said bar for movement if and only if all the tools are angularly aligned with their opposite indicating elements.

12. In apparatus for sorting articles, a plurality of portable indicating holders for receiving individual articles, a plurality of indicating elements carried by each said holder, each said element being individually settable in a plurality of indicating positions; code sensing mechanism including a plurality of axially movable tools having working ends adapted to engage said indicating elements, a support for said tools, means for moving said holders to a code sensing position adjacent said support with their elements axially aligned with said tools, said tools and said elements having on their axially aligned ends cooperating transverse ribs and grooves which intermesh only when angularly aligned, spring means biasing said tools to a normal position in which said working ends project from said support, said tools being movable inwardly of said support against said spring means, said tools having apertures therein spaced from said working ends, a bar on said support movable transversely of said tools and carrying pins aligned with said apertures when said tools are in their normal positions, resilient means operable to move said bar transversely of said tools, said tools being effective when moved inwardly of said support to move their apertures out of alignment with said pins and block transverse movement of said bar, means operable to move said support into engagement with a holder in said code sensing position, said elements being effective when said support engages said holder to move said tools inwardly of the support if said axially aligned ends of the tools and elements are not also angularly aligned and ineffective to move the tools inwardly if the ends of the tools and elements are angularly aligned, and means operable after movement of the support into engagement with the holder to drive said resilient means, and a control device connected to said bar for movement if and only if all the tools are angularly aligned with their opposite indicating elements.

13. Apparatus for sorting articles as defined in claim 12, in which said holders are provided with grippable elements, and said control device comprises means operable to grip said grippable elements upon movement of said bar so that a holder gripped thereby follows the movements of said support, latch means to hold said grip means in its gripping position, and means for releasing said latch means.

14. Apparatus for sorting articles as defined in claim 12, in which said holders are provided with openable bottoms, and said control device comprises means operable to open said bottoms upon movement of said bar.

15. Apparatus for sorting articles, comprising a plurality of detached portable indicating holders for receiving individual articles, a plurality of indicating elements permanently carried by each said holder, each said

element being individually settable in a plurality of indicating positions; a sorting station comprising trunk conveyor means for conveying holders thereto, branch conveyor means for conveying holders therefrom, code sensing means operable to sense the positions of the indicating elements on a holder, means including said code sensing means for gripping a holder on said trunk conveyor means having its elements set in a predetermined code, and means including said gripping means for transferring said gripped holder from said trunk conveyor means to said branch conveyor means.

16. In apparatus for sorting articles, a plurality of portable indicating holders for receiving individual articles, a plurality of indicating elements carried by each said holder, each said element being individually settable in a plurality of indicating positions; a sorting station comprising trunk conveyor means for conveying holders thereto, branch conveyor means for conveying holders therefrom, code sensing mechanism including a plurality of axially movable tools having working ends adapted to engage said indicating elements, a support for said tools, said trunk conveyor means being effective to move said holders to a code sensing position with their elements axially aligned with said tools, said tools and said elements having on their axially aligned ends cooperating transverse ribs and grooves which intermesh only when angularly aligned, spring means biasing said tools to a normal position in which said working ends project from said support, said tools being movable inwardly of said support against said spring means, said tools having apertures therein spaced from said working ends, a bar on said support movable transversely of said tools and carrying pins aligned with said apertures when said tools are in their normal positions, resilient means operable to move said bar transversely of said tools, said tools being effective when moved inwardly of said support to move their apertures out of alignment with said pins and block transverse movement of said bar, means operable to move said support toward and away from said code sensing position, said elements being effective when said support engages said holder to move said tools inwardly of the support if said axially aligned ends of the tools and elements are not also angularly aligned and ineffective to move the tools inwardly if the ends of the tools and elements are angularly aligned, and means operable after movement of the support into engagement with the holder to drive said resilient means, and grippable members on said holders, and means connected to said bar for movement thereby to grip said members only if all the tools are angularly aligned with their opposite indicating elements, so that a holder gripped thereby follows the movements of the support, said support moving means being operable to move a gripped holder to said branch conveyor means, and means for releasing said gripping means.

17. Apparatus for sorting articles, comprising a plurality of detached portable indicating holders for receiving individual articles, a plurality of indicating elements carried by each said holder, each said element being individually settable in a plurality of indicating positions; a sorting station including a plurality of receiving bins, means for conveying said holders to said receiving bins, code sensing means at each bin operable to sense the settings of the indicating elements on the holders, said holders being operable to discharge the articles carried thereby, and means including said sensing means to open the holders of its classification to deliver the articles therefrom into said bin.

18. Apparatus for sorting articles as defined in claim 17, including return conveyor means, and means to transfer the emptied holders to said return conveyor means.

19. Apparatus for sorting articles as defined in claim 17, including means for closing the opened holders.

20. Apparatus for sorting articles as defined in claim 1, in which the sum of the numbers of classifications transferred to said branch conveyor means at all said junc-

tions by the several setting sensing means and transfer means is equal to said plurality of classes, so that all the holders of all the classifications are removed from the trunk conveyor means and transferred to the plurality of branch conveyor means.
